UNITED STATES PATENT OFFICE.

OSCAR WOODWARD, OF NEW YORK, N. Y., ASSIGNOR TO WYCKOFF, SEAMANS & BENEDICT, OF ILION, NEW YORK, A CORPORATION OF NEW YORK.

TYPE-WRITING MACHINE.

SPECIFICATION forming part of Letters Patent No. 777,169, dated December 13, 1904.

Application filed September 2, 1903. Serial No. 171,584. (No model.)

To all whom it may concern:

Be it known that I, OSCAR WOODWARD, a citizen of the United States, and a resident of the borough of Manhattan, city of New York, in 5 the county of New York and State of New York, have invented certain new and useful Improvements in Type-Writing Machines, of which the following is a specification.

My invention relates to type-cleaning devices for type-writing machines; and the object of said invention is to provide a simple, cheap, and efficient device of the character specified and one which can be readily attached to or detached from a type-writing machine. 10 To the above and other ends, which will hereinafter appear, my invention consists of the features of construction, arrangements of parts, and combinations of devices to be hereinafter described, and particularly pointed out 15 in the appended claims.

In the drawings, wherein like reference characters indicate corresponding parts in the various views, Figure 1 is a fragmentary perspective view of a sufficient number of parts 20 of one character of type-writing machines to illustrate my invention in its application thereto. Fig. 2 is a front-to-rear vertical sectional view of the same with parts broken away. Fig. 3 is a detail central vertical sectional 25 view of the type-cleaning device, the section being taken on the line $\alpha\alpha$ of Fig. 2 and looking in the direction of the arrow in said figure. Fig. 4 is a detail side view of one of the brush-heads.

I have shown my device applied to a No. 6 Remington machine, and sufficient of such machine is shown to illustrate my invention in the application thereto.

The frame of a type-writing machine comprising the corner-posts 1 and top plate 2 has mounted therein by hangers 3 a circular series of type-bars 4, which are connected by links 5 to the usual key-levers. (Not shown.) Extending upwardly from the top plate 2 are 40 risers 6, which support one of the traverse- rods 7, upon which the carriage 8 is supported and guided in its movement from end to end of the machine. The top plate of the machine is apertured at 9 for the passage of the

ribbon 10 across the type-well 11 of the machine. This ribbon is guided in its movement by a guide-plate 12, pivoted at one end at 13, so that the free end thereof may swing upwardly to its position shown in Fig. 1. A shift-rail 14 constitutes a bearing for the carriage, at the front side thereof, and is effective to shift the platen and its frame for upper and lower case writing. Connected to the shift-rail 14 is a block 15, which extends downwardly and forwardly from the shift-rail and is provided at its forwardly-projecting portion with a pointer 16, that co-operates with the indices upon the carriage-scale 17. The features thus far described constitute portions of the well-known No. 6 Remington machine, 55 and a further description thereof is unnecessary.

The frame 18 of the type-cleaning device is bent at 19, so as to form a groove in the forward end thereof, that is adapted to receive 70 the shift-rail 14 of a type-writing machine. This grooved portion is apertured at 20 in order to receive the depending block 15 on the shift-rail, so as to enter the same and prevent a longitudinal movement of the frame 18 on 75 the shift-rail, as will hereinafter more clearly appear. The frame 18 is bent upwardly to form parallel side supports 21, which have openings therein constituting bearings for the horizontal shaft 22, said shaft being loosely 80 disposed for rotation and having a limited longitudinal movement in said bearings by reason of which in the ordinary operation of the device the brush will be constantly shifted widthwise to bring different portions of its 85 surface in contact with the type. A rotary vertically-disposed brush 23 is provided with heads 24, that may be secured to the brush by rivets 25 or screws 26 or by any other suitable means, and these heads are apertured 90 near the centers thereof, as indicated at 27. The shaft 22 extends through central openings in the brush-heads, and pins or screws 28 are received in suitable openings in the shaft on each side of the brush. The heads of these pins or screws extend laterally from the shaft and are of such dimensions and are so disposed that a portion of the head of each

screw 28 is seated in the aperture 27 in the associated brush - head, so as to cause the brush to rotate with the shaft and to prevent a longitudinal movement of the brush on the 5 shaft. It will be seen that by removing the screws 28 the shaft 22 may be longitudinally withdrawn from its bearings in the side plates 21 and from the brush, so that a new brush may be readily substituted for an old one 10 when desired. The frame 18 is provided with an opening 29, through which the brush projects, as indicated in Figs. 2 and 3. The rear end of the frame has suitably secured thereto, as by screws 30, a spring-plate 31, which ex- 15 tends rearwardly and upwardly from its point of connection to the frame and is bent at 32 to form a groove by means of which the spring may be seated on and secured to a rod 33 on the carriage 8. The pressure of the spring- 20 plate 31 is sufficient to clamp the device between the shift-rail 14 and carriage-rod 33 and to maintain the frame and brush over the type-well of the machine when the carriage is thrown back, as indicated in Fig. 1, at the 25 same time permitting the ready disengagement and removal of the type-cleaning device. The spring 31 is provided with the indentation α , so that its function will not be interfered with.

30 The shaft 22 has a crank-arm 34, which carries a handle 35 and by means of which the shaft and brush may be rotated and given the slight axial movement.

In using the type-cleaning device the carriage is first thrown back to the position illustrated in Fig. 1, and the ribbon-guide 12 is swung to the position therein shown, when the ribbon is thrown to one side, so as to fully expose the type-well. The type-cleaning device may then be secured in position by first placing the device fore and aft of the machine and centrally of the type-well, with the grooved portion 32 of the clamping-spring against the carriage - bar 33 and exerting a 40 rearwardly and downwardly directed pressure against the spring until the grooved portion 19 of the frame receives the shift-rail 14 and the block 15 is seated within the opening or aperture 20 in the frame. It will therefore be understood that the pressure exerted by the spring is sufficient to hold the frame in place over the type-well and that the lug 15 will prevent a lateral movement of the frame along the shift-rail. The frame is thus secured in position centrally of the type-well and in a position where any of the types on the various type - bars may be brought into contact with the face of the brush, as indicated in Figs. 1 and 2, by depressing the key. 50 The turning of the crank-handle at this time will cause the brush to be rotated, and an incidental longitudinal movement of the shaft will be effected, so as to give an axial movement to the brush, as well as to rotate it, thereby thoroughly cleansing the type-faces by the 65

movement of the brush across the type-faces in various directions. The back - and - forth longitudinal movement of the shaft in its bearings is limited by the heads of the screws 28, which are adapted to bear against the inner 70 faces of the side supports 21 of the frame. The cleaning device may be readily removed by pressing the front end of the frame upwardly and rearwardly until the grooved portion 19 thereof is disengaged from the shift-rail and block 15. A finger-piece 36 may be provided in order to facilitate the positioning of the device or disengagement of it from the type-writing machine.

From the foregoing description it will be 80 seen that a simple, cheap, and efficient type-cleaning brush is provided and one which may be readily attached to or detached from the type-writing machine to afford an individual cleaning of the type or types carried by each 85 type-bar and that a natural oscillation or axial movement of the brush is effected while it is being rotated by the crank-handle, so that the brush will move across the type-faces in various directions and a thorough and efficient 90 cleansing of the type may be accomplished.

What I claim as new, and desire to secure by Letters Patent, is—

1. A device of the character specified comprising a brush, means for actuating said 95 brush, and a supporting-frame for the brush, said frame being constructed to be removably secured to a portion of the carriage and shift-rail of a type-writing machine.

2. A device of the character specified comprising a brush, means for actuating said 100 brush, a supporting-frame for the brush, and spring-pressed means for removably securing said frame to the carriage and shift-rail of a type-writing machine.

3. A device of the character specified comprising a brush-frame that is adapted to engage the shift-rail of a type-writing machine, a spring that is connected to said frame and is adapted to bear upon the carriage of the 110 machine to removably support said frame in place, a brush movably mounted in said frame, and means for moving the brush on said frame.

4. A device of the character specified comprising a brush-frame that is grooved to receive the shift-rail of a type-writing machine, a grooved spring that is connected to said frame and is adapted to bear upon the carriage of the machine to removably support said frame in place, a rotary brush mounted in said 120 frame, and means for rotating the brush on said frame.

5. A device of the character specified comprising a brush-frame that is grooved to receive the shift-rail of a type-writing machine, a grooved spring that is connected to said frame and is adapted to bear upon the carriage of the machine to removably support said frame in place, a rotary brush mounted in said 125 frame, means for rotating the brush on said 130 frame,

- frame, and means for preventing an accidental displacement of said brush-frame longitudinally of the shift-rail.
6. A device of the character specified comprising a brush-frame having means that engage the shift-rail and carriage of a type-writing machine to removably support the frame in place, said engaging means including a spring, bearings in said frame, a horizontally-disposed shaft mounted in said bearings, and a brush mounted on said shaft.
7. A device of the character specified comprising a brush-frame having means that engage the shift-rail and carriage of a type-writing machine to removably support the frame in place, bearings in said frame, a horizontally-disposed shaft mounted to turn and to move axially in said bearings, and a brush mounted on said shaft.
8. A device of the character specified comprising a brush-frame having means that engage the shift-rail and carriage of a type-writing machine to removably support the frame in place, said engaging means including a spring, bearings in said frame, a horizontally-disposed shaft mounted to turn and to move axially in said bearings, a brush mounted on said shaft, and a crank connected directly to said shaft for turning it.
9. A device of the character specified comprising a brush-frame having a groove that is adapted to receive the shift-rail of a type-writing machine, a grooved spring that is connected to said brush-frame and bears against the carriage to removably support the frame in place, bearings in said frame, a horizontally-disposed shaft mounted to turn and to move axially in said bearings, a brush mounted on said shaft, and a crank connected directly to said shaft for turning it.
10. A device of the character specified comprising a rotary brush, means for supporting said brush over the type-well of a type-writing machine, means for turning said brush, and means for affording an axial movement of the brush during the turning movement thereof.
11. A device of the character specified comprising a frame that is adapted to extend fore and aft of a type-writing machine over the type-well thereof and to be supported and removably secured at its opposite ends to the machine, a rotary brush supported by said frame and rotating on a horizontal axis, and means for rotating said brush and for simultaneously moving it back and forth axially.
12. A device of the character specified comprising a frame that is adapted to extend fore and aft of a type-writing machine over the type-well thereof and to be supported and removably secured at its opposite ends to the machine, a horizontal shaft loosely disposed in bearings in said frame for an axial as well as a rotary movement, a brush secured to said shaft, and means for rotating the shaft.

13. A device of the character specified comprising a brush-supporting frame, means for supporting said frame over the type-well of a type-writing machine, a horizontally-disposed shaft that rotates and moves axially in bearings in said frame, a brush that is secured to said shaft by removable pins that take into the shaft and limit the axial movement of the shaft, and a crank secured directly to the shaft. 70
14. A device of the character specified comprising a brush-supporting frame, means for supporting said frame over the type-well of the type-writing machine, a horizontally-disposed shaft that rotates and moves axially in bearings in said frame, a brush, the heads of which are apertured, and removable pins that take into the shaft and which are seated in the apertures in the heads of the brush to cause the brush to turn with the shaft and to prevent an axial movement of the brush on the 85 shaft, said pins likewise limiting the axial movement of the shaft in its bearings. 75
15. A device of the character specified, comprising a brush-supporting frame that is apertured for the passage of the brush and has upwardly-projecting sides with bearing-openings therein, a horizontally-disposed shaft seated loosely in said bearing-openings for rotation and longitudinal movement therein, a crank secured to said shaft, a brush on the 90 shaft between the upwardly-projecting sides, and means for securing the frame to a type-writing machine and above the type-well thereof. 95
16. A device of the character specified comprising a brush-frame that is grooved to cooperate with a portion of the machine that is independent of the carriage, and a grooved spring that is adapted to be seated on a portion of the machine to removably secure the brush-frame against movement over the type-well, a brush on said frame, and means for actuating said brush on its frame. 100
17. A device of the character specified comprising a brush-frame that is supported by the shift-rail of the machine and by a portion of the carriage, a spring for removably securing said frame in place, a brush carried by the brush-frame, and means for actuating the brush on its frame. 110
18. A device of the character specified comprising a brush-supporting frame adapted to be supported upon a type-writing machine, and a brush that is loosely disposed in bearings in said brush-frame to receive a rotary 120 and an axial movement. 115
19. A device of the character specified comprising a brush-supporting frame, a shaft loosely disposed to rotate and move axially in bearings in said frame, a brush that is secured to said shaft by removable pins carried by said shaft, and means for rotating the shaft. 125
20. A device of the character specified comprising a brush-supporting frame, a shaft supported in bearings in said frame, a brush, the 130

brush-heads of which are apertured, and removable pins that are carried by the shaft and are seated in the apertures in the heads of the brush to cause the shaft to turn and to prevent an axial movement of the brush on the shaft.

5 Signed in the borough of Manhattan, city of

New York, in the county of New York and State of New York, this 29th day of August, A. D. 1903.

OSCAR WOODWARD.
